UNITED STATES PATENT OFFICE.

EPPA H. RYON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

NEEDLE-LOOM.

SPECIFICATION forming part of Letters Patent No. 743,107, dated November 3, 1903.

Application filed July 17, 1902. Serial No. 115,921. (No model.)

To all whom it may concern:

Be it known that I, EPPA H. RYON, a citizen of the United States, residing at Worcester, in the county of Worcester and State of Massachusetts, have invented certain new and useful Improvements in Needle-Looms, of which the following is a specification.

My invention relates to needle-loom for weaving narrow-ware fabrics, such as ribbons. In this class of looms a series of narrow-ware fabrics or ribbons are woven on one loom, each fabric being woven separately by a separate needle mechanism.

The object of my invention is to improve upon the construction of the needle mechanism for weaving said fabric as now ordinarily made, and more particularly to have each needle mechanism independently operated on the forward and backward beat of the lay.

20 The mechanism for operating the needle to move it in and out of the shed is located on the lay and moves with the lay. The pivotal point of the needle is so located that at the forward beat of the lay to the fell of the fabric the reed is in substantially the same line or plane as the pivotal support of the needle.

25 In my improvements I provide a spring blade or guide through the free end of which the thread passes before passing to the needle. I also provide a needle with a turned-up free end or point through which the filling-thread passes.

30 My invention consists in certain novel features of construction of my improvements, as will be hereinafter fully described.

I have shown in the drawings only one needle mechanism; but it will be understood that there is a series of these needle mechanisms extending across the loom in the direction of the width of the loom and that each needle mechanism is independent of the other needle mechanisms.

35 Referring to the drawings, Figure 1 is a detached plan view of a portion of the lay and breast-beam with my improvements applied thereto. The lay is shown in its forward position. Fig. 2 corresponds to Fig. 1, but shows the lay in its rear position and the parts of the mechanism in the opposite posi-

tion from that shown in Fig. 1. Fig. 3 is a section on line 3 3, Fig. 1, looking in the direction of arrow *a*, same figure. Fig. 4 is a section on line 4 4, Fig. 2, looking in the direction of arrow *b*, same figure. Fig. 5 corresponds to Fig. 1, but shows a modified construction of my mechanism. Fig. 6 is a plan view of the shuttle-holder detached. Fig. 7 is a side view of the shuttle-holder and shuttle therein looking in the direction of arrow *c*, Fig. 6. Fig. 8 is a plan view of the shuttle detached; and Fig. 9 is a detached detail showing the attachment of the end of the link to the operating-arm, as will be hereinafter described. Fig. 10 is a detached detail showing a side view of the pivotal connection of the shuttle-supporting arm shown in Fig. 5, as will be hereinafter described. Figs. 6 to 10 are shown on an enlarged scale.

In the accompanying drawings, 1 is the breast-beam.

2 is a stand secured to the inner side of the breast-beam and extending out therefrom in a horizontal plane. To the arm 2' of the stand 2 is in this instance adjustably secured by a bolt 3' a plate 3, having a bearing 3" at 70 its outer end for a vertically-extending shaft 4, which has secured upon its upper end a collar 4' and the inner end of the oscillating needle 5. The needle 5 preferably has an upwardly bent or curved end 5', with a hole 80 therein through which the thread passes. The shaft 4, which is the pivotal point of the needle, is located in such a position that at the forward beat of the lay to the fell of the fabric said shaft will be substantially in the 85 same line or plane as the reed. (See Fig. 3.)

On the lower end of the shaft 4 is secured an arm 6, carrying a pin or roll 6', (see Fig. 3,) which extends into and travels in an inclined or cam slot 7' in the plate 7, in this 90 instance adjustably secured by screws 7" to a bar or plate 8, extending in a longitudinal groove or recess in the upper side of the lay 9. (See Fig. 3.)

To the outer slotted end of a side extension 95 2" of the stand 2 is adjustably secured in this instance by a bolt 10' the end of a curved bracket or arm 10, upon the outer slotted end

of which is adjustably secured by a bolt 11' the shuttle-holder 11, containing a shuttle 12 therein.

The shuttle 12 carries the selvage or tie thread 13, which forms, in connection with some of the warp-threads, the selvage on the woven fabric 14, which passes over the rod or roll 15, mounted in bearings 16, secured upon the inner side of the breast-beam 1 in 10 the usual way.

On the edge of the plate 3 is in this instance secured one end of a blade or guide 17, which has at its end a hole through which passes the filling-thread 18 to and through the upturned end 5' of the oscillating needle 5. The blade or guide 17 acts as a tension for the filling-thread.

The operation of my improvements will be readily understood by those skilled in the art. Supposing the lay to be in its forward position, as shown in Fig. 1, on the rearward movement of the lay as the roll 6' on the arm 6 reaches the outwardly-inclined portion of the slot 7' the continued backward movement of the lay causes the rotation of the shaft 4 and the consequent oscillating or swinging movement of the needle 5 to move it into the open shed formed by the warp-threads 19 19 (shown in Fig. 3) and carry the filling-thread 18 with it and into the shuttle-holder 11 and over the shuttle 12. As the lay moves forward from the position shown in Fig. 2 the inclined portion of the slot 7', through the roll 6' on the arm 6 traveling therein, rotates the shaft 4 and moves the needle 5 back out of the shed to its first position, causing the filling-thread 18 to pass under the shuttle 12 and out of the shuttle-holder 11 and back through the shed, to be beaten up by the reed as the lay moves to its forward position. (Shown in Fig. 1.)

In the modified construction shown in Fig. 5 a slight vibratory motion in a horizontal plane is communicated to the shuttle-holder 11 and to the shuttle 12 at the proper time to move the shuttle toward and away from the fabric as it is being woven.

In Fig. 5 at the end of the said extension 2" of the stand 2 is a hub 2'', forming a bearing 45 for a vertical shaft 23, on the upper end of which is fast the end of the bracket or arm 10", corresponding to the bracket or arm 10 in Figs. 1 to 4. To the lower end of said shaft 23 is fast one end of an arm 22. (See Fig. 55 10). The other end of said arm 22 has pivoted thereto one end of a link 21. The other end of said link 21 is connected by a pin 21' to the hub of the arm 6, fast on the vertical rotating shaft 4, (see Fig. 9,) to move with said 60 hub.

It will be seen that the rotation of the shaft 4, as the needle 5 moves into and out of the shed will communicate motion to the link 21 and,

through the arm 22, a slight rotating motion to the shaft 23 to cause the supporting-arm 65 10" and the shuttle-holder 11 to move the same toward and away from the fabric as it is being woven.

The shuttle 12 preferably has an offset spring 12' on one side, which acts as a tension- 70 spring for the thread in the shuttle.

The advantages of my improvements will be readily understood by those skilled in the art. The mechanism for oscillating the needle is of simple construction and a positive 75 motion is communicated to the needle into and out of the shed. The blade or guide 17 produces the proper tension on the filling-thread.

It will be understood that the details of construction of my improvements may be varied, if desired.

Having thus described my invention, what I claim as new, and desire to secure by Letters Patent, is—

1. In a needle-motion of a loom, the combination with the oscillating needle having its free end bent or turned to extend out of the plane of the body of the needle for the filling-thread to pass through said end, and 90 a tension blade or guide stationary at one end for the filling-thread to pass through its free end before passing to the needle, substantially as shown and described.

2. In a needle-motion of a loom, the combination with the breast-beam and a support extending out therefrom, a needle pivotally mounted on said support, a shuttle-supporting arm and a shuttle-holder on said arm, and a shuttle in said holder, of a lay, and a plate 100 having a cam-groove therein attached to the lay, to operate the needle through intermediate mechanism, and said mechanism, substantially as shown and described.

3. In a needle-motion of a loom, the combination with the breast-beam, of a supporting-stand, an arm secured to said stand carrying a shuttle-holder, and said shuttle-holder, and an oscillating needle, and connections intermediate said needle and the shuttle-holder 110 supporting arm, to communicate a slight oscillating motion to the shuttle-holder and the shuttle, on the movement of the needle, substantially as shown and described.

4. In a loom, the combination with a shuttle-holder and a shuttle held thereby to supply a selvage or tie thread, of a swinging or oscillating needle having its free end bent or turned to extend out of the plane of the body of the needle and provided with an eye for the 120 filling-thread to pass through, substantially as shown and described.

EPPA H. RYON.
